UNITED STATES PATENT OFFICE.

WALTER BOYD VANDIGRIFT, OF DUNWOODY, GEORGIA.

TOY.

Application filed March 28, 1922. Serial No. 547,497.

To all whom it may concern:

Be it known that I, WALTER B. VANDIGRIFT, a citizen of the United States, residing in Fulton County, near Dunwoody, 5 State of Georgia, have invented certain new and useful Improvements in Toys; and I do hereby declare the following to be a full, clear, and exact description of the invention, such as will enable others skilled in the 10 art to which it appertains to make and use the same.

The present invention relates to toys, and aims to provide a novel and improved toy 15 including an acrobatic figure and novel means for mounting the toy and setting it in motion, for the amusement and entertainment of children.

With the foregoing and other objects in view, which will be understood as the 20 description proceeds, the invention resides in the construction and arrangement of parts, as hereinafter described and claimed, it being understood that changes can be made within the scope of what is claimed 25 without departing from the spirit of the invention.

The invention is illustrated in the accompanying drawing, wherein the figure is a 30 perspective view of the toy.

The frame of the toy includes an arch 1 having the standards 2 and top yoke or lintel 3. Such arch is supported by two pairs of legs or braces 4 at the opposite sides, each pair of legs or braces being inclined in opposite directions and crossing one another. The legs or braces are pivoted, at their 35 points of crossing, on bolts 5 engaging through the standards 2 of the arch, whereby when the clamping and pivot bolts 5 are loosened, the legs can be swung into proper position against the floor or supporting surface on which the arch 1 rests, or the legs or braces can be swung into position adjacent to and parallel with the standards 2, 40 when folding the device to be shipped or stored away. By tightening the bolts 5 the legs or braces are clamped either in supporting position, as illustrated, or in folded position.

An acrobatic articulated figure 7 is carried by a rotatable shaft 6 having its terminals mounted for rotation in the standards 2 of the arch, and said figure may be in the

form of an animal or a human being, which ever is preferred. The figure comprises the 55 body 8 having the arms 9 and legs 10 pivotally connected thereto, the arms being secured to the shaft 6, so that the body 8 dangles loosely from the arms, while the legs 10 are loosely supported from the body, 60 in order that the turning or rotary movement of the shaft will give the figure life-like acrobatic movements to the amusement and entertainment of the onlookers.

In order to set the figure 7 in motion, an 65 arm 11 is secured to the shaft 6 and depends therefrom, as shown, and is provided with a target 12 to be struck by an object for imparting turning motion to the shaft 6 and figure 7.

A cross bar 13 is secured to the standards 70 2 below the shaft 6, and a rubber band or elastic 14 is secured at one end to said bar below and spaced from the arm 11, and has a ball 15 or other member at the free end thereof to strike the target. Thus, in operating the toy, the frame is held by one hand and the member 15 pulled away from the target 12 to stretch the elastic 14, and the operator then lets go of the member 15 75 aiming at the target 12. If the aim is good, the member 15 strikes the target and this will either impart a swinging motion to the arm 11 and figure 7, or if the target is struck hard enough, the arm and figure are 80 caused to turn completely around one or more times with the shaft 6. The arm 11 and figure 7 will come to rest in depending position, as shown, to bring the target into 85 position to be struck by the member 15.

The elastic 14 being secured to the frame at below or beyond the margin of the target 90 12 will require some skill in causing the member 15 to strike the target; it being necessary to give said member an upward motion when directed toward the target or said member may not strike the target.

By loosening the bolts 5 and swinging the 95 braces or legs adjacent to the standards 2, the toy can be compactly stored away or placed in a flat box.

Having thus described the invention, what is claimed as new is:

A toy comprising a pair of standards, a 100 rotary shaft mounted in said standards, a cross bar secured to said standards below

the shaft, an articulated figure carried by said shaft, an arm secured to said shaft and depending therefrom, said arm having a target at its lower end, an elastic secured to said cross bar below said target, and a member secured to said elastic to strike said target when properly directed over the cross

bar, said figure and arm being disposed between the standards to rotate with the shaft above the cross bar.

In testimony whereof I have signed my name to this specification.

WALTER BOYD VANDIGRIFT.
